UNITED STATES PATENT OFFICE.

IRVING C. JENNINGS, OF SOUTH NORWALK, CONNECTICUT.

SEWAGE EJECTOR.

Application filed April 11, 1923. Serial No. 631,459.

To all whom it may concern:

Be it known that I, IRVING C. JENNINGS, a citizen of the United States, residing at South Norwalk, county of Fairfield, State of Connecticut, have invented certain new and useful Improvements in Sewage Ejectors, of which the following is a specification.

The present invention relates to apparatus for periodically charging a closed vessel with fluid and thereafter emptying the same. More particularly, the invention relates to sewage ejectors.

At the present time, one of the principal systems for ejecting sewage from receivers comprises a receiver having an inlet and an outlet, each provided with a check valve, a float device within the receiver, a pipe having communication with the receiver and acting alternately as a vent and a means for supplying compressed air, valve mechanism controlled by the float device for admitting compressed air to the receiver to expel its contents, and an air vent valve also controlled by said float device.

This system is rather complicated and expensive inasmuch as it requires a large storage tank for the compressed air, a relief valve for said tank, float mechanism and two valves, one controlling the supply of compressed air and the other the vent of air from the receiver, and automatic mechanism for opening and closing these valves.

It is the principal object of the present invention to simplify these old constructions and to provide a dependable, comparatively simple and inexpensive fluid ejecting system.

More particularly, the present invention aims to provide an apparatus in which the storage tank for the compressed air, the complicated float device and separate automatically controlled air supply and air vent valves are eliminated.

To these ends, an air compressor is employed of the type in which, when the pump is idle, there is a free passage or communication between the inlet and outlet ports of the compressor but, when the pump is in operation, this communication is cut off. A compressor of the rotary type employing liquid for its pumping action, such as the well known Nash-Hytor compressor, may be employed. The discharge of this compressor is connected by means of a pipe with the receiver so that, when the compressor is idle, a vent is automatically provided for the re-

ceiver, permitting fluid to flow into the same. When the compressor is in operation, however, this vent is cut off and compressed air is supplied to the receiver to eject liquid that has accumulated therein.

Other objects and features of novelty will be apparent from the description taken in connection with the drawings, in which:

Figure 1 is a sectional elevation of a sewage ejecting apparatus constructed in accordance with the present invention.

Figure 2 is a sectional elevation of the compressor showing the position of the liquid employed therein, when the compressor is idle.

Figure 3 is an elevation of the compressor and the motor for driving the same and shows, diagrammatically, the switch for controlling the motor.

Figure 4 is an end view of the compressor showing, in section, a separator on the inlet side thereof.

Figure 5 is a longitudinal sectional elevation of the compressor.

Referring to the drawings, the numeral 10 indicates a liquid receiver which, as shown, is adapted to receive sewage and is located in a concrete pit. The receiver is provided with a removable cover plate 11 to permit access to the interior thereof, when necessary. The receiver also has an inlet 12 and an outlet 14, each provided with a check valve 13 and 15 respectively. In operation, fluid, such as sewage, flows by gravity into the receiver through the inlet 12, passing by the check valve 13. After the receiver is filled up to the desired point, the fluid is expelled through the outlet 14. For this purpose, compressed air is admitted to the receiver through the pipe 16, a compressor C of a particular type being provided to supply this air.

In order that the fluid may flow into the receiver, it is necessary that there be an air vent therefrom. According to the present invention, the compressor employed is of the type which, when idle, has a free passage or communication from its outlet to its inlet, so that the air vented from the receiver may pass freely through the pipe 16, the compressor and out through its inlet. When the compressor is in operation, this communication is cut off so that the air vent is thus automatically closed. The well known Nash-Hytor compressor is an illustration of the type employed. This

type of compressor comprises a casing 20 which may be described as elliptical and a rotor operating therein. The rotor consists of a hub 21 having a plurality of curved, outwardly extending blades 22 connected at their sides by shrouds 23. Thus, the blades form a circular series of radially extending pockets which are adapted to be alternately brought into communication 10 with the inlet ports 24 and outlet ports 25, formed in the sides of the casing 20. The compressing action is obtained by employing a liquid, such as water, indicated by the reference numeral 26. When the compressor is in operation, the liquid turns with the rotor, but due to centrifugal force follows the periphery of the casing and thus forms an elliptical ring, as shown in Figure 1. It will be observed that the water 15 alternately recedes from and re-enters the rotor pockets, twice in each revolution. When the pockets of the rotor come opposite the inlet ports 24, the water recedes, permitting air to flow in and this charge 20 of air, as the pockets approach the outlet ports 25, is compressed by the water re-entering the pockets, acting like pistons. The compressed air is delivered through the outlet ports to the conduit 16 which 25 communicates with the receiver 10. Obviously, when the compressor is in operation, the inlet and outlet ports are thus effectively sealed from each other, by the elliptical ring of water. However, when the 30 compressor stops, the water subsides or collects at the bottom of the casing, as shown in Figures 2 and 5, thus placing the inlet and outlet ports in communication. The heads 29 of the compressor are made large 35 enough so that the water will fall to a sufficiently low level to uncover the ports. The compressor may be supplied with liquid, when necessary, through a pipe such as indicated at 30.

If it is desired to automatically control the operation of the compressor, any suitable means may be provided for this purpose. As shown, a ball float 31 is disposed within the receiver 10, being carried by the 40 pivoted arm 32. This arm controls a pilot switch 33 of any suitable type. This pilot switch, by means of the conductors 34, is electrically connected with an automatic switch 35 which controls the supply of energy from the mains 36 to the motor 37, the switch 35 being connected with the motor 37 by the electrical conductors 38.

In operation, the fluid, such as sewage, flows into the receiver through the inlet 45 12, the air in the receiver being vented through the pipe 16 and the compressor. When it reaches a predetermined high level in the receiver, indicated by the upper dotted line position of float 31, Figure 1, the 50 float closes switch 33, in turn causing the

closing of the automatic switch 35 and thus setting in operation the motor 37. The rotor of the compressor, which is directly connected to the motor, is then set in rapid rotation, causing the water seal to assume the 55 elliptical ring form shown in Figure 1, thereby effectively sealing the inlet and outlet ports 24 and 25 from each other and causing air to be taken in through the inlet ports, compressed and delivered through the outlet ports to pipe 16 above the surface of the liquid within the receiver 10. The liquid or sewage within the receiver is thus expelled from the same through the outlet 14, the check valve 13 preventing any 60 back flow through conduit 12. When the liquid within the receiver reaches a predetermined low level, such as indicated by the lower dotted line position of the float 31, Figure 1, the float opens the pilot switch 33, which in turn causes the automatic switch 35 to open, thus stopping the motor and compressor; the water within the compressor dropping to the position shown in Figure 2, thus placing the inlet and outlet 65 ports of the compressor in communication with the pipe 16, and thus providing a vent for the receiver 10.

When the compressor is stopping and the water falling to the position shown in Figure 2, thus opening up the inlet and outlet ports, there may be a rush of compressed air from the outlet back through the inlet ports, carrying water therewith. To catch this water, a separator 39 may be provided, the same being inserted in the inlet line of the compressor. Any water that collects in this separator may be returned to within the casing 20 by a return pipe 40.

Although an embodiment of the invention 105 has been described in detail, it is to be understood that it is not limited to the exact construction shown but includes modifications and changes which come within the scope of the appended claims.

What I claim to be new and desire to secure by Letters Patent is:

1. The combination with a receiver having an inlet and outlet and means to prevent back flow therethrough, of a compressor having its discharge opening connected to said receiver, said compressor being of the type wherein the inlet and outlet ports are in communication when the compressor is idle, thereby providing a vent for the receiver, but are not in communication when the compressor is in operation.

2. The combination with a receiver having an inlet and outlet and means to prevent back flow therethrough, of a compressor having its discharge opening connected to said receiver, said compressor being of the type wherein the inlet and outlet ports are in communication when the compressor is idle, thereby providing a vent for 130

the receiver, but are not in communication when the compressor is in operation, and means controlling the operation of said compressor in accordance with the amount of fluid in the receiver.

3. The combination with a receiver having an inlet and outlet and means to prevent back flow therethrough, of a compressor having its discharge opening connected to said receiver, said compressor being of the rotary type employing fluid for its compressing action, wherein the inlet and outlet ports are in communication when the compressor is idle, thereby providing a vent for the receiver, but are not in communication when the compressor is in operation.

4. The combination with a receiver having an inlet and outlet and means to prevent back flow therethrough, of a compressor having its discharge opening connected to said receiver, said compressor being of the rotary type employing fluid for its compressing action, wherein the inlet and outlet ports are in communication when the compressor is idle, thereby providing a vent for the receiver, but are not in communication when the compressor is in operation, and means controlling the operation of said compressor in accordance with the amount of fluid in the receiver.

5. A periodically operating ejector system, comprising a receiver for the fluid to be ejected, inlet and outlet conduits provided with check valves communicating with said receiver, an air conduit communicating with said receiver, a compressor communicating with said air conduit, said compressor having a liquid seal adapted during the operation thereof to cut off communication between the inlet and outlet ports of said compressor and adapted to effect communication between said ports when the compressor stops, a motor operating said compressor, means to set said motor in operation when the fluid reaches a predetermined high level in said receiver to cause the compressor to deliver compressed air to said receiver and eject the fluid therefrom, and to stop said motor when the material reaches a predetermined low level, the liquid seal then automatically effecting free communication between the atmosphere and receiver to permit fluid again to flow thereto.

6. A periodically operating ejector system, comprising a receiver for the material to be ejected, inlet and outlet conduits provided with check valves communicating with said receiver, an air conduit communicating with said receiver, a compressor communicating with said air conduit, said compressor having a liquid seal adapted during the operation thereof to cut off communication between the inlet and outlet ports thereof and adapted to effect communication be-

tween said ports when the compressor stops, means to set said compressor in operation when the material reaches a predetermined high level in said receiver to deliver compressed air to said receiver and eject the material therefrom and to stop said compressor when the material reaches a predetermined low level, the liquid seal then automatically effecting free communication between the atmosphere and receiver through the compressor to permit material to flow again thereto.

7. A periodically operating ejector system, comprising a closed receiver for the material to be ejected, an air conduit communicating with said receiver, a compressor having an outlet port communicating with said air conduit, said compressor having a liquid seal adapted during the operation thereof to cut off communication between the inlet and outlet ports thereof and adapted to effect communication between said ports when the compressor stops, means to set said compressor in operation when the material reaches a predetermined high level in said receiver to deliver compressed air to said receiver and eject the material therefrom and to stop said compressor when the material reaches a predetermined low level, the liquid seal then automatically effecting free communication between the atmosphere and receiver through the compressor, to permit the material to flow again into said receiver.

8. A periodically operating ejector system, comprising a closed receiver for the material to be ejected, inlet and outlet conduits provided with check valves communicating with said receiver, an air conduit communicating with said receiver, a compressor having an outlet port communicating with said air conduit, said compressor having means for effecting free communication between the inlet and outlet ports thereof when idle, means to set said compressor in operation when the material reaches a predetermined high level in said receiver to deliver compressed air to said receiver and eject the material therefrom and to stop said compressor when the material reaches a predetermined low level, said means then automatically effecting free communication between the atmosphere and receiver through the compressor, to permit the material to flow again into said receiver.

9. A periodically operating ejector system, comprising a closed receiver for the material to be ejected, inlet and outlet conduits provided with check valves communicating with said receiver, an air conduit communicating with said receiver, a compressor having an outlet port communicating with said air conduit, said compressor having a liquid seal adapted during the operation thereof to cut off communication between its inlet and

- outlet ports and adapted to effect communication between said ports when the compressor stops, an electric motor operating said compressor, a float in said receiver, a 5 switch controlling said motor operated by said float, whereby when the material reaches a predetermined high level in said receiver the motor circuit is closed and the compressor is set in operation to deliver 10 compressed air to the receiver and eject the material therefrom and when the material reaches a predetermined low level the circuit of the motor is broken to stop the compressor, said liquid seal then automatically 15 effecting free communication between the receiver and atmosphere through said compressor to permit material to flow again into said receiver.
10. A sewage ejector system, comprising 20 a closed receiver, inlet and outlet sewage conduits having check valves communicating with said receiver, an air conduit communicating with said receiver, an air compressor communicating with said air conduit, said compressor having a liquid seal adapted during the operation thereof to cut 25 off communication between its inlet and outlet ports and adapted to connect said ports when the compressor stops, a motor operating 30 said compressor, means to set said motor in operation when the sewage reaches a predetermined high level in said receiver to cause the compressor to deliver compressed air to said receiver and eject the sewage 35 therefrom and to stop said motor when the sewage reaches a predetermined low level, the liquid seal then automatically effecting free communication between the atmosphere and receiver through said compressor to permit sewage again to flow into said receiver. 40
11. A sewage ejector system, comprising a closed receiver, inlet and outlet sewage conduits having check valves communicating with said receiver, an air conduit communicating with said receiver, a compressor having an outlet port communicating with said air conduit, said compressor having a liquid seal adapted during the operation of the 45 compressor to cut off communication between its inlet and outlet ports and adapted to effect communication between said ports when the compressor is idle, an electric motor operating said compressor, a float in said sewage receiver, a switch controlling said 50 motor operated by said float, whereby when the sewage reaches a predetermined high level the compressor is set in operation and delivers compressed air to said receiver, ejecting the sewage therefrom, and whereby 55 when the sewage reaches a predetermined low level the compressor stops, the liquid seal therein automatically effecting communication between the atmosphere and receiver through the compressor, to permit 60 sewage to flow again into said receiver. 65
12. A sewage ejector system, comprising a closed receiver, inlet and outlet sewage conduits having check valves communicating with said receiver, an air conduit communicating with said receiver, an air compressor 70 having an outlet port communicating with said air conduit, said compressor comprising an elliptical casing and a rotor operating therein having a plurality of radially extending pockets open at their outer ends, said 75 compressor having inlet and outlet ports adapted to communicate with the inner ends of said pockets periodically during the operation of the pump and having a liquid seal adapted to assume an annular form under 80 centrifugal action, thus sealing the outer ends of said pockets and cutting off communication between the outlet and inlet ports, means to set said compressor in operation when the sewage reaches a predetermined 85 high level in said receiver and for stopping the compressor when the sewage reaches a predetermined low level, said liquid seal then subsiding and effecting free communication between the receiver and atmosphere 90 to permit the sewage to flow into said receiver.
13. The combination with a liquid receiver having an inlet and outlet, means for preventing back flow therethrough, an air 95 compressor connected thereto, and means whereby the compressor will be set in operation at a high level of liquid in the receiver and thrown out of operation at a low level thereof. 100
14. The combination with a liquid receiver having an inlet and outlet, means for preventing back flow therethrough, an air compressor connected thereto, means whereby the compressor is set in operation at a high level of liquid in the receiver and thrown out of operation at a low level thereof, the compressor being connected and arranged so that the admission and vent of air from the receiver will be controlled 105 by the starting and stopping of the pump. 110
15. The combination with a liquid receiver having an inlet and outlet, means for preventing back flow therethrough, an air compressor connected thereto, a motor for 115 driving the air compressor, means whereby the motor is set in operation at a high level of liquid in the receiver and thrown out of operation at a low level thereof and connections whereby the admission and vent of air from the receiver will be controlled 120 by the starting and stopping of the motor. 125
16. The combination with a liquid receiver having an inlet and outlet, and means for preventing back flow therethrough, of an air compressor connected thereto, means whereby the compressor is set in operation at a high level of liquid in the receiver and thrown out of operation at a low level thereof, and an air vent controlled by the pump 130

which allows the air in the receiver to escape when the pump is thrown out of operation.

17. The combination with a liquid receiver having an inlet and outlet, and means for preventing back flow therethrough, of an air compressor connected thereto, means whereby the compressor is set in operation at a high level of liquid in the receiver and thrown out of operation at a low level thereof, and an air inlet and vent controlled by the pump which allows the air in the receiver to escape when the pump is thrown out of operation.

18. The combination with a liquid re-

ceiver having an inlet and outlet, and means for preventing back flow therethrough, of an air compressor connected thereto, means whereby the compressor is set in operation at a high level of liquid in the receiver 20 and thrown out of operation at a low level thereof, and an air inlet and vent controlled by the pump which allows air to pass to the pump when it is in operation and which allows the air in the receiver to escape 25 when the pump is thrown out of operation.

In testimony whereof I hereunto affix my signature.

IRVING C. JENNINGS.
